SIGNORS TO MOTOR TERMINALS COMPANY, OF WILMINGTON, DELAWARE, A COR-
PORATION OF DELAWARE

CONTROLLER FOR LOCKS OF DEMOUNTABLE CONTAINERS

Application filed February 13, 1931. Serial No. 515,515.

This invention relates to door locking mechanism for demountable containers, so arranged that the deposit of the container on its support may automatically lock the door or leave it unlocked, according to a predetermined setting of the mechanism on the container.

In its preferred form, our invention provides, in the base of the container, a depending member which is adapted to be raised by engagement with an upstanding actuator when the container is on a suitable support carrying such actuator; the raised member is adapted to cause the locking of the door or not according to a previous setting of shiftable means on the container, and the shiftable means may for instance, comprise the depending locking member, or the door bolt with which it may coact. Therefore, the setting of the shiftable member may enable the mere placing of the container on the support to automatically lock the door of the container, or to leave the door locking mechanism idle, notwithstanding the deposit of the container on that support.

We have shown, in the drawings hereof, different embodiments of our invention, and have hereinafter more fully described the same, and have set out the essential novel features in the claims.

In the drawings, Fig. 1 is an end elevation of a truck and a demountable body in the act of being raised therefrom, the parts being equipped with the door locking device; Fig. 2 is a vertical section through the rear end of the body and truck platform, as indicated by the line 2—2 on Fig. 1; Fig. 3 is a sectional elevation on the line 3—3 of Fig. 2 looking from the interior of the container toward the door; Fig. 4 is a similar view showing the parts in different position; Figs. 5, 6, 7 and 8 are details illustrating various positions of the coacting locking lever and door bolt; Figs. 9 and 10 are sectional sections through the rear end of a demountable body having a modified form of locking system; Figs. 11 and 12 are vertical sections on the line 11—11 on Fig. 10 but illustrating the parts in different position; Figs. 13 and 14 are vertical sections in a plane corresponding to Fig. 11

but showing a modified form of locking mechanism; Fig. 15 is a horizontal section on the line 15—15 on Fig. 13.

As shown in Fig. 1, A indicates the floor of a suitable truck or other vehicle, and B a demountable body adapted to be placed thereon. Suitable means are provided for positioning the body on the vehicle, as for instance, upstanding conical corner projections ⁵⁵ *a* adapted to engage sockets in a base frame ⁶⁰ of the body in accordance with Patent No. 1,772,939 of B. F. Fitch. While we have shown only a truck for supporting the body, this is to be understood as illustrative of any vehicle or support, as for example a flat car ⁶⁵ or a stationary platform.

The demountable body B as shown herein may comprise a substantially rectangular container having suitable doors in its walls. We have shown only one pair of doors *b* in ⁷⁰ the end wall of the container, but this is to be taken as illustrative of doors placed in any wall.

Each pair of doors *b* is provided with a suitable latching device and with a lock to ⁷⁵ cooperate therewith, which lock is operated by the deposit of a body on a predetermined support, but may or may not be effective, according to the setting of the container.

As shown in Fig. 2, the latching device ⁸⁰ which is shown in latched position comprises a pair of upright bolts 10 and 11, slidably guided by housings 12 and 13 on the inner face of the door. The inner ends of the bolts are secured to a rocking head 15 which is rigid on a horizontal shaft 16 mounted in the door. On the outer side of the door this shaft rigidly carries a handle 17.

By oscillating the handle 17, the head 15 is rocked, which forces outwardly or draws inwardly, as the case may be, the inner ends of the two bolts 10 and 11, so that they may be projected behind transverse members of the container, as for instance, behind the lintel member 8 above the door, and behind the sill member 9 below it, as shown in Fig. 2, or may be drawn respectively upwardly and downwardly to clear such members. The extreme ends of the housings 12 and 13 have substantially round holes guiding the bars ⁹⁰ ⁹⁵ ¹⁰⁰

at these points, whereas the adjacent walls of the housings have transverse slots enabling the pairs to swing as the member 15 is rocked.

When the latching bolts are in the position shown in Fig. 2, they retain closed the door which carries the bolts, and this door, by overlapping the other door, holds that door closed. We mount on the door which does not carry the shaft 16, a suitable clip 28 which the handle 17 is adapted to abut when the doors are raised, and then a suitable sealing wire 29 may be passed through an opening in the clip and around the handle, thus sealing the container doors closed.

Sometimes the goods in a container are intended for a single destination, and the shipper desires to automatically lock the container in addition to the sealing wire or padlock when it is deposited on the transporting vehicle, and retain it locked until the container is removed, thus preventing pilfering in transit. At other times, the goods in the container are not intended for the same destination, and the shipper desires to allow possibility of access to the container by unlocking the padlock or breaking the seal. The mechanism we have provided allows the shipper to readily select which system of locking he will employ and after he has set the container accordingly and closed the doors, the system cannot be changed until the door is opened.

We have shown several methods of carrying out our controllable locking system on the container. The first described is shown in Figs. 3 to 8 inclusive. In these figures, the locking bolt 11 is provided with a sleeve 20 which has a laterally projecting lip 21. This sleeve is normally pressed downward by a compression spring 22 surrounding the bolt 11 and bearing against the upper end of the sleeve and a collar 24 of the bolt. When the bolt projects at right angles to the door 7, as shown in Fig. 2, a suitable notch 25 at the lower end of the sleeve registers with a lateral projection 14 on the bolt and retains the sleeve in this position. This is the position for automatic locking, as about to be explained.

Mounted in the floor of the container is a box-like housing 30, having in its upper wall an opening 31, through which the lower portion of the sleeve 20 extends. This housing 30 has a pair of downwardly extending wings 32, carrying a pin 33 on which is pivotally mounted a bell crank 35. This bell crank has an upwardly extending arm 36 which is adapted to overhang the lip 21 of the sleeve. When the lip 37 of the bell crank over-hangs the sleeve lip, as shown in Figs. 2 and 3, it is impossible to raise the sleeve or bolt 11, and accordingly the doors are tightly locked. This overhanging takes place if the container with the sleeve set as described, is deposited

on the support equipped with means to engage the bell crank and swing it, such means being illustrated as a stirrup *a1* secured to the floor of the truck A of the member. Normally the bell crank lies by gravity in the position shown in broken lines in Fig. 3, so that the lip 37 is idle irrespective of the position of the sleeve 20. When the sleeve is in its active position, as shown in Figs. 2, 3 and 5, then if the container is deposited on the stirrup carrying support, the sleeve 37 is swung over the lip 21, as shown in Fig. 5, and the door is automatically locked.

Now, when the shipper desires to prevent the possibility of this automatic locking, he simply raises the sleeve 20 before the door is closed and turns it at right angles to its locked position, bringing it into the position shown in Fig. 8 with the lip 21 lying parallel with the door. The sleeve is then held in this position by reason of the bolt lock 14 engaging another notch in the lower end of the sleeve. With the lip in this position, it is entirely immaterial as to the position of the bell crank, and in no case does it have any restraining influence on the door latching mechanism.

In place of shifting the bolt member into and out of position to coat with the bell crank lip, we may shift the bell crank itself so that it may or may not coat with a lip on the bolt 11 of the door latch. Such construction is illustrated in Figs. 9 to 12 inclusive. In this case, the box-like housing 30a in the floor of the container is somewhat wider than before and the pivot pin 33a somewhat longer, and the bell crank 35 which is made the same as before, is slidable on this pivot pin. When the bell crank lock is to be active, it is retained in position where it may cooperate with a lip 18 on the lower end of the bolt 11 by means of a distance block 40 which occupies the space between the bell crank and the housing wall 38 back of the same. On the other hand, to hold the bell crank in position where it is always idle, the block 40 is removed and the bell crank is shoved back against the wall 38 and the block replaced in front of it between the bell crank and front wall 39 of the housing, as shown in Fig. 10. In this position, the action of the bell crank is immaterial, as it can never engage the lip 18 of the door bolt.

The block 40 may be formed as shown in Figs. 9 to 12, and have a diagonal notch 41 at its lower portion so that when shoved downwardly from the inserting position in Fig. 12, it will be guided laterally into its terminal position, as shown in Fig. 11, where the upper end of the block is flush with the car floor. Then, a suitable pin 45 may be inserted behind the block preventing its lateral movement, and thereby preventing its upper movement. This construction prevents any displacement of the block 40 from below when the container is elevated. When the parts are once set from

the interior of the container, they can only be changed from the interior. The block is shown as having suitable recesses 42 on one face and 43 on the other to accommodate the 5 lips of the bell crank and bolt and allow free movement of each of them.

It will be seen that when this construction is employed, the shipper, before he closes the 10 container, simply sets the bell crank in its active or inactive position, as desired, and thereafter, while the container door is closed, this setting cannot be changed. The bell crank normally stands in the position shown in Fig. 11 and is thus out of the range of the bolt 15 lip 18, irrespective of the setting of the bell crank on its pivot bolt, but if the container is deposited on a support having the stirrup a_1 positioned to engage the bell crank, the latter is then swung into a position which is active or otherwise, according to the previous 20 setting of the bell crank on its pivot pin. If desired, the stirrup a_1 may be narrow enough to engage the bell crank only when it is shifted into the active position toward the end of the 25 container as illustrated in Figs. 9 and 10, but this is immaterial as the swinging of the bell crank when shifted away from the bolt 11 is idle.

In Figs. 13, 14 and 15, instead of shifting the bell crank on its pivot pin, we have enlarged the housing 30b laterally, so that the bell crank may be swung beyond its normal elevated position into an idle position and have provided a locking bolt 50 for retaining it in this idle position. This bolt passes down through a lip in the housing 30b and through an opening 51 in the lip 37 of the bell crank, and may thus retain the bell crank in position where it is ineffective whether or 35 not it is deposited on a container having the abutment a_1 . When the bell crank is to be active, the pin is put in place in the housing lip in position where it will stand behind the bell crank lip and prevent the bell crank 40 being swung to idle position, as shown in Fig. 14. This is a very simple arrangement. The shipper, if he wishes the automatic locking of the container to destination, simply places the pin 50, as shown in Fig. 14 and allows the bell crank 35 to be swung up into engagement with the stirrup a_1 on the supporting platform. On the other hand, if he wishes access to the container during transit, he swings the bell crank into the abnormal position 45 shown in Fig. 13 and Fig. 1, and by passing the pin 50 into the bell crank opening 51, maintains it idle for all purposes and in all 50 positions of the container.

It will be seen that whichever system is 60 employed for controlling the automatic locking, that we have enabled the shipper to determine whether the container shall be locked from the time of its deposit to the time of its delivery, or otherwise. The housing containing the door locking bell crank is so near the

door, that it is not covered by the lading within the container, and accordingly the attendant may set the bell crank at any time during the loading operation if the container is equipped with that type of controlling 70 device. If the type having the adjustable sleeve on the door bolt is employed, that may also be set at any time previous to the closing of the doors. In any case, after the doors are closed and locked or sealed, the setting 75 cannot be changed without unlocking the doors or breaking the seal.

We claim:

1. The combination with a container, mechanism for locking the same rendered active or idle automatically upon the deposit of a container on the support, according to a predetermined setting of a controlling device on the container. 80

2. The combination of a container, a locking device adapted to act automatically when the container is deposited on a suitable support, and means on the container for rendering the locking device idle. 85

3. The combination of a container, a door locking mechanism therefor, and an adjustable controller on the container adapted to enable the mechanism to be locked or remain unlocked automatically upon the deposit of the container on a support. 90

4. The combination of a container having a door, a latch for the door, a lock carried by the container and adapted to coact with means on a support for locking the latch, and means on the container for rendering 100 such act nugatory.

5. The combination of a container having a door, a latching device for the door, a lock for the latching device, said lock being adapted to engage a suitable abutment when the container is deposited, and means on the container for determining whether the locking device shall lock the latch or leave it free. 105

6. The combination of a container, a lock therefor, a support for the container, an abutment carried by the support and adapted to coact with the lock to move it from an idle position to one potentially active, and means on the container for determining whether such potential activity shall be effective. 110

7. The combination of a container having a door and door latching mechanism, of a lock on the container adapted to be operated automatically by positioning the container on a suitable support, said lock and door latch being adapted to coact with each other, and means for moving one of them to prevent such coaction. 120

8. The combination of a container, mechanism adapted to lock the same automatically on the deposit of the container on a predetermined support, and a controlling device on the container and accessible only from within the container for predetermining the 125

setting of the locking device to render it continuously idle or potentially active, as desired.

9. The combination of a container having a door, a locking device for the door adapted to act automatically when the container is deposited on a suitable support, and means on the container inaccessible when the door is closed for rendering the locking device idle.

10. The combination of a container having a door with a latching device, a swinging gravity lock adapted to coact with the latching device and be operated automatically upon the placing of a container on a predetermined support, and means for holding the gravity lock in an idle position.

11. A demountable container having a door, a locking device therefor including a counterweighted member tending to move to unlocked position, but adapted to be moved into a potentially active position by engagement with a support having a proper abutment, and means for changing the coaction between the door and locking device to render said potential position non-effective.

12. The combination of a container having a door, a downwardly extending latch bolt therefor having a shoulder, a counterweighted bell crank carried by the container and having a lip adapted to overhang the shoulder carried by the latch bolt when the bell crank is locked, a support having an abutment adapted to engage the bell crank and rock it into a position which may be active, and means for withdrawing the shoulder on the bolt to prevent its coaction with the bell crank lip.

13. The combination of a container having a door, a bolt carried by the door, a slideable sleeve on the bolt having a projecting lip, a rocking bell crank mounted in the base of the container and having a lip adapted to overhang the lip of the sleeve or clear the same, according to the engagement of an arm of the bell crank with an abutment, said sleeve being adapted to be turned on the bolt to an idle position, and means for holding it idle.

14. The combination of a door having a locking bolt, a sleeve slideable on the bolt and having a projecting lip, a spring acting on the sleeve, said sleeve having a pair of shoulders co-acting with a projection on the bolt whereby the spring may hold the sleeve with the lip projecting away from the door or substantially parallel therewith, and a rocking device carried by the container and having a lip adapted to be swung into position to overhang the lip of the sleeve when the sleeve is active, said rocking device having means whereby it may engage a suitable abutment to rock it into the position described.

15. The combination of a container having a door, a latch bolt therefor, a rocking device having a lip adapted to overhang the latch bolt, a support having an abutment adapted

to engage the rocking device to rock it into a position which may be active, said rocking device being shiftable along its pivotal support, and means for holding it in its constantly inactive or its potentially active position as desired.

16. The combination of a container having a door, a locking device therefor, a support having an abutment adapted to engage the locking device to move it into a position which may be active, said locking device being shiftable along its pivotal support, and a block adapted to be positioned on one side or other of the locking member and thereby hold it in position where it is necessarily inactive or in position where it may be active.

17. A container having a door, a rocking member carried in the base of the container and adapted to be swung by engagement of a suitable abutment to lock the door, and means on the container for holding the rocking member in an idle position where it cannot engage the abutment.

18. The combination of a container having a latch bolt therefor, a bell crank having a lip adapted to overhang the latch bolt and having an arm adapted to engage an abutment on a suitable support to rock the bell crank from an idle position at one side of the latch bolt into coaction therewith, and means for holding the bell crank with its lip in an idle position on the other side of the latch bolt, the operating arm of the bell crank being retained high enough so that it cannot engage the abutment.

19. The combination of a container having a door, a latch bolt therefor, a housing in the base of the container into which the latch bolt may extend, a bell crank mounted in the housing having a lip adapted to overhang a lip on the latch bolt and having an arm adapted to engage an abutment on a suitable support, and a pin adapted to engage the housing and bell crank and lock it in a position where it is out of engagement with both the latch bolt and the abutment.

In testimony whereof, we hereunto affix our signatures.

ALBERT H. BATES.
